UNITED STATES PATENT OFFICE

2,662,730

POWER LINE LIFT POLE

Wayne B. Crawford, Houston, Tex.

Application October 31, 1950, Serial No. 193,055

1 Claim. (Cl. 254—184.3)

1

This invention relates to improvements in devices for elevating power lines on poles and specifically the insulators thereof.

It is the primary object of this invention to provide an improved attachment for a pole to be used for the purpose of raising energized power lines upward or away from their normal position to enable workman to change or repair insulators, crossarms or other equipment at the top of power line poles, said attachment having extensible rods for adjustment purposes and the rods being so arranged that they are capable of being pivotally swung by means of a lifting device so that the power line may be moved upwardly without the necessity of endangering the workman.

Ancillary objects and features of importance will become apparent in following the description of the illustrated form of the invention.

In the drawings:

Figure 1 is an elevational view of a typical pole with a part of the attachment applied to the pole;

Figure 2 is an elevational view of the same pole illustrated in Figure 1 but showing the complete attachment thereon;

Figure 3 is a vertical sectional view taken substantially on the line 3—3 of Figure 2 and in the direction of the arrows, portions being shown in elevation;

Figure 4 is a perspective view of the mounting plate and mounting assembly;

Figure 5 is a perspective view of the support which is adapted to connect to the pole;

Figure 6 is an enlarged fragmentary sectional view showing a ratchet means of extending one of the pole sections with respect to the other;

Figure 7 is a fragmentary sectional view of the structure in Figure 6, and;

Figure 8 is a longitudinal sectional view of one of the rods which is adapted to hold the power line in elevating it.

As shown in the drawings the device is adapted to be used primarily in connection with power lines, for example the line 10 which is located near the insulator 12 carried by the pole 14. Other insulators are located on the cross member 16 of the pole 14 these insulators being of standard construction and held in place by standard means.

Attention is first invited to Figure 5 where there is illustrated a support generally indicated at 18 and consisting of a plate 20 which has an upper lug 22 fixed thereto, this upper lug being provided with a ball. There is a lower lug 24, 55

2

also provided with a ball and another lower lug 26 spaced from it. An upper clamp member 28 is attached to the upper part of the plate 20 and has a chain 30 arranged to be disposed in the slot 32 in the clamp member 28. This chain is adapted to encircle a part of the pole 14 in holding the plate 20 fixed thereto.

There is a lower clamp fixed to the plate 20, this lower clamp consisting of a clamp member 34 having a slot 36 therein which is arranged to receive the chain 38. Both the chain 30 and the chain 38 have threaded shanks 40 at their outer ends with wing nuts 42 thereon so as to pull the chain tightly in place on the pole 14.

There is a mounting plate or mounting plate assembly 44 (Figure 4) which is adapted to be removably fixed to the pole 14 at a place spaced from the support 18. The mounting plate assembly 44 consists of a panel 46 which has an upper clamp member 48 and a lower clamp member 50. These clamp members are identical to the clamp members 28 and 34 and have chains operatively connected therewith in order to hold the panel 46 in a fixed position on the pole 14.

There are apertures 52 and 54 formed in the panel 46, these apertures being used to accommodate hooks at the ends of pulleys 56 and 58, the functions of which will be described subsequently.

An upper sleeve 60 is fixed to the panel 46 and there is a lower sleeve 62 also fixed to this panel but spaced from the first mentioned sleeve 60. These sleeves form parts of guides and have threaded elements, for example set screws 64 and 66 carried thereby.

There is a bracket 68 connected to the panel 46 near the lower edge thereof and substantially between the apertures 52 and 54.

As disclosed in Figure 2 the mounting plate assembly 44 and the support 18 are arranged to hold three substantially identical rods or rod assemblies 70, 72 and 74 respectively. The rod assembly 70 (Figure 8) consists of a tubular section 76 which is provided with a lateral opening 78 and a reduced shank 80 serving as an axial extension thereof. A socket 82 is fixed to the extension 80 and arranged to be connected to the ball of the lug 24, to connect the rod 70 to the lug for swivel movement. The second section 84 of the rod is preferably round wood stock and it has a line clamp 86 or a substitute of standard description at the outer end thereof. There is a metal row of teeth 88 attached to a sleeve 85 on the section 84 and the teeth 88 extend from one edge of the section 84, these teeth

being engaged by the gear 90. The lower end of the tubular section 76 is provided with a metal liner 87 to provide a smooth sliding surface. An outer liner (unshown) may be used for strength purposes at the lower end of section 76.

The gear 90 is mounted on a shaft 92, this shaft having square ends which pass through openings in the opposite sides of a casing 94. This casing is fixed, as by the U-bolts 96 which pass through openings in the flanges 98 and 100 of the case, around the tubular section 76 of the rod 70 and is so located that the gear 90 is passed through the opening 78 in the tubular section 76.

Ratchets 102 and 104 are fixed to the same shaft 92 as the gear 90 and are engaged by the spring loaded dogs 108 and 110. Therefore, when a winding tool is placed on either end of the shaft 92 and the shaft rotated, the inner section 84 of the rod 70 is operated outwardly of the tubular section 76 and held in place by the action of the ratchets and dogs. This lengthens the rod 70.

There is a guide provided for the rod 70, this guide consisting of a guide arm 116 which is pivoted to a bracket 118, this bracket being fixed to the tubular section 76 of the rod 70. The guide arm 116 is passed through the sleeve 62 and may be held in place within this sleeve through the action of the said screw 66.

Means for raising the rod 70 and hence a line which is held in the clamp 86 thereof, is attached to the bracket 118. The preferable means consist of a line 120, for example a rope or flexible cable, this line 120 extending around the guide pulley 56 and also around the guide pulley 122 which is connected pivotally to the bracket 118. Ultimately, the end of the line 120 is fixed to a part of the pulley assembly 122.

In operation the line is held in the clamp 86 and then the rod may be extended to the desired length. Upon pulling the line 120 the rod 70 is pivotally operated about the lug 24 as a pivot point, this action causing the outer end of the rod 70 to be moved in an arc, carrying with it the line which is held by the clamp 86.

The rod 74 is of identical construction to the rod 70 and operates in an identical manner. The guide arm 126 for the rod 74 passes through the sleeve 60 and is held in place in selected positions by means of the set screw 64.

The rod 72 is of slightly different construction

insofar as the mounting is concerned. The lower end thereof is arranged to be held to the lug 22 by means of the socket, but the rod 72 is held fixed to the mounting plate assembly by means of the bracket 68 which has a pin 134 passed through aligned openings therein. This pin also passes through openings in a plate 136 which is carried by the mounting assembly 138 on the tubular section of the rod 72.

10 In operating the device one or more of the rods may be used at the same time. It may well be that the pole has only one insulator thereon and, therefore, it is unnecessary to use the rods 70 and 74. If the pole has more than one insulator and if more than one line is to be moved, installed or otherwise handled, more than one of the illustrated rods may be employed.

Having described the invention, what is claimed as new is:

20 For use with a power line pole, an attachment for lifting a power line on the pole comprising a support attachable to the pole, a telescopic extensible rod including outer and inner sections, means swivelly connecting the outer section to 25 said support for vertical swinging of said extensible rod, means on the inner section for holding a line, means operatively connected to said sections for extending the extensible rod, a mounting plate attachable to said pole above said support, a bracket on said inner section, a cable and 30 pulley for swinging said extensible rod connected to said bracket and mounting plate to cause vertical swinging of the extensible rod upon extension of said rod, and a guide rod for said extensible rod pivoted to said bracket and slidably and 35 swivelly connected to said mounting plate for sliding by extension of said extensible rod.

WAYNE B. CRAWFORD.
